SPINNAKER SAIL

Edward V. Willis, Port Washington, N.Y.

Application January 15, 1948; Serial No. 2,352

5 Claims. (Cl. 114—103)

1

This invention relates to a spinnaker or balloon sail.

An object of the invention is to provide an improved spinnaker sail adapted to take advantage of the upward thrust of the wind and thus tend to lift the boat out of the water thereby decreasing skin friction of the water on the boat.

Another object of the invention is to provide a spinnaker sail with less tendency to oscillate and therefore easier to control and to make "sleep."

Another object of the invention is to provide an improved spinnaker sail having a high degree of fullness in its upper portion.

Another object of the invention is to provide a spinnaker sail having an increased amount of cloth which is not "taxable."

Another object of the invention is to provide a spinnaker sail having straight lateral edges or leeches.

Another object of the invention is to provide an improved spinnaker sail comprising two portions of equal width each being shaped on the top edge so that the outer edge is longer than the inner edge by a distance equal to the width of each sail portion.

Another object of the invention is to provide a spinnaker sail which is simple and inexpensive to make and efficient in use both going before the wind and on a close reach.

Other objects of the invention will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the drawings, in which,

Figure 1 is a perspective view showing a portion of a boat with a spinnaker sail embodying the invention hoisted thereon;

Figure 2 is a diagrammatic view indicating how two sail halves may be cut and joined together to form a sail embodying the invention;

Figure 3 is a detail view, partly cut away, showing the construction of a portion of a lateral edge or leech of the sail; and

Figure 4 is a side elevational view of a hoisted sail as shown in Figure 1.

In the embodiment of the invention shown herein the sail comprises the two portions 10 and

2

12. The outer lateral edges 14 and 16 respectively of each of said sail portions are cut straight. The inner edges of said sail portions, along substantially the lower two-thirds, represented by the numerals 18 and 20 respectively, are also cut straight and may be sewn together by a line of stitching substantially parallel to the outer edges or leeches of the assembled sail. It is to be understood that each of said sail portions may comprise a number of strips which may be inclined with respect to said edges 18 and 20 respectively.

At the top the sail portions 10 and 12 are cut more or less diagonally from their outer edges 14 and 16 respectively, inwardly to points on the inner edges of said sail portions respectively which are below the top of said edges by a distance equal to the width of said sail portions, which in the embodiment of the invention illustrated herein is substantially one-third of the length of the sail portions along their outer edges respectively. Thus in shaping the upper portion of the sails, a distance X, equal to the distance Y, which is the width of a sail portion, may first be measured off from the top of the outer edges of said sail portions as indicated in Figure 2. Then the dotted line 22 perpendicular to the outer edge of the sail portion will indicate at its point of intersection with the inner edges of said sail portions, the upper extremities of the straight inner edge portions 18 and 20 respectively. This point of intersection, which is indicated herein by the letter F, also indicates the lower extremity of the top edge of each sail portion. The dotted line 24 represents a diagonal line extending from the upper extremity E of the lateral edges of said sail portion to the point F which has been established as described above. Preferably, however, the upper edge of the sail portions 10 and 12 respectively is not formed by cutting along this diagonal line 24. Instead it is preferred to form a curved upper edge extending above the diagonal line 24 thus providing each sail portion with the roaches 26 and 28 respectively. The top portions of the two sail portions are then sewed together along the upper margin of said roaches 26 and 28 thus forming a seam 30 extending vertically of the sail along its mid-line from the peak or head P for a distance substantially equal to the width of a sail portion 10 or 12. When the sail portions 10 and 12 have been sewn together along the vertical inner edges 18 and 20, and along the margins of the upper reaches 26 and 28, the resulting sail will be substantially oval in shape and will form a pocket

adapted to take advantage of the upward thrust of the wind in an efficient manner thereby tending to lift the boat out of the water and in so doing to decrease the area of surface of the boat in contact with the water. The effect therefore is to decrease the skin friction between the water and the boat and to make the boat go faster.

A spinnaker formed as described above has a larger portion of fullness near the top and the wind striking any portion of the sail is deflected upwardly thus tending to lift the boat as has been stated. The sail thus includes near its top a large amount of cloth which is not "taxable."

The term "taxable" is used herein to mean that the increased amount of cloth which is provided in the sail, due to having the outside edges of the sail parts parallel and not angled inwardly toward the top, will not subject the user to penalty in sailing races. The rules specify the height of a sail for a given class of boat. The increase 20 in width near the top without increasing the height of the sail for a given class of boat thus does not disqualify the boat for racing in its class or subject it to giving handicap.

It is known that wind ordinarily moves along a 25 path which is inclined slightly upward. It has been computed that this upward angle is approximately 4 degrees (Aerodynamics of Sails, by Dr. Manfred Curry, 14, second paragraph). A spinnaker sail formed as described herein is well 30 adapted to take full advantage of this upward thrust of the wind, and to convert even a thrust of the wind parallel to the water into an upward thrust tending to lift the boat.

While the bottom edges 32 and 34 of the sail 35 portions 10 and 12 respectively may be somewhat curved thus forming a roach at the bottom edge of the sail, the outer lateral edges or leeches 14 and 16 are made straight as has been described. I have found this desirable since roaches along 40 the leeches or lateral extremities of the sail are impossible to control and tend to flap thereby disturbing the equilibrium of the sail. With the straight edges I have found it much easier to control the sail and make it "sleep" and thus be more efficient. If desired the edges 14 and 16 may be reinforced by means of a wire 36 embedded in a fold provided by turning back a narrow edge portion of the sail.

Along the lower edges of the sail nips or triangular gathers 38 may be provided at intervals to reduce the width of the sail along its bottom edge and thus aid in promoting the ballooning out of the sail when it is filled with wind, and also contribute to the control of the sail since the shortened length of the bottom edge tends to prevent flapping of the sail along the lower edge.

The sail may be hoisted as indicated in Figure 1 by securing the upper end or peak or head P of the sail to the mast as by a halyard 40 and by securing one lower corner of the sail to the extremity of the boom 42, and securing the other lower corner of the sail to the front of the boat by the rope 43.

It will thus be seen that there has been provided by this invention a method and apparatus in which the various objects hereinabove set forth together with many thoroughly practical advantages are successfully achieved. As various possible embodiments might be made of the mechanical features of the above invention and as the art herein described might be varied in various

parts, all without departing from the scope of the invention, it is to be understood that all matter hereinbefore set forth or shown in the accompanying drawing is to be interpreted as illustrative and not in a limiting sense.

What I claim is:

1. A spinnaker sail comprising two parts sewn together along their inner edges, each part having a long outer edge and an inner edge comprising a lower portion parallel to said outer edge, and an upper portion cut substantially diagonally from a point on the said outer edge, which is above the top of the said lower portion of the inner edge by a distance substantially equal to the width of said sail part, along a transverse section taken to the top of said lower portion of the inner edge.

2. The sail as claimed in claim 1 in which roaches are provided along the said upper portions of the inner edges of said sail parts respectively.

3. The sail as claimed in claim 1 in which the upper portions of the inner edges of said sail parts respectively are defined by roaches.

4. A spinnaker sail comprising two parts sewn together along their inner edges each part having a long outer edge and an inner edge comprising a lower portion parallel to said outer edge and an upper portion extending outwardly and upwardly to a point adjoining said outer edge, the said outer edges of said parts being substantially parallel in the assembled sail.

5. A spinnaker sail comprising two parts each having a bottom edge, an outer edge substantially perpendicular to said bottom edge, and an inner edge comprising a lower portion extending substantially at right angles to said lower edge a distance less than the height of the outer edge substantially equivalent to the width of the sail 35 part between said lower portion of the inner edge and the said outer edge, and an upper portion extending from the top of said inner edge lower portion to the top of said outer edge along a curved line having its center in a transverse plane below the lower end of the upper portion of said inner edge and thus defining a roach extending beyond a diagonal line joining the upper end of the lower portion of said inner edge and the top of the said outer edge, said sail parts being sewn 40 together along their inner edges thus providing a sail assembly characterized by the fullness of its top portion.
